CLAIM

The ornamental design for a housing portion of an exercise device, as shown and described herein.

DESCRIPTION

FIG. 1 is a front elevational view of a housing portion of an exercise device showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is a perspective view thereof on an exercise device.

Those portions of the housing portion of an exercise device shown in broken lines are included for illustrative purposes only and form no part of the claimed design.

Those portions of the exercise device shown in broken lines are included to denote nature and environmental use of the claimed design and form no part of the claimed design.

1 Claim, 8 Drawing Sheets
